DESIGN FOR A HYDRAULIC JACK

Herbert E. Page, Alhambra, Calif.

Application December 30, 1944, Serial No. 117,159

Term of patent 14 years

(Cl. D41—1)

To all whom it may concern:

Be it known that I, Herbert E. Page, a citizen of the United States and resident of the city of Alhambra, county of Los Angeles, State of California, have invented a new, original, and ornamental Design for Hydraulic Jack, of which the following is a specification, reference being had to the accompanying drawings, forming a part thereof, in which:

Fig. 1 is a perspective view on a reduced scale of a hydraulic jack, showing my new design;

Fig. 2 is a top plan view thereof with the handle shown in Fig. 1 omitted for convenience of illustration;

Fig. 3 is a side elevational view of Fig. 2;

Fig. 4 is a rear elevational view; and

Fig. 5 is a front elevational view thereof.

I claim:

The ornamental design for a hydraulic jack, substantially as shown.
